UNITED STATES PATENT OFFICE.

CHARLES H. GAGE, OF NEW YORK, N. Y.

GARMENT-HANGER.

No. 846,023.

Specification of Letters Patent.

Patented March 5, 1907.

Application filed March 15, 1906. Serial No. 306,123.

To all whom it may concern:

Be it known that I, CHARLES H. GAGE, a citizen of the United States, residing at the city, county, and State of New York, have 5 invented certain new and useful Improvements in Garment-Hangers, of which the following is a full, clear, and exact description.

My invention relates to garment-hangers, 10 and is adapted particularly for skirts and coats.

My object is to provide a simple, inexpensive, and effective article of manufacture which will be easy to adjust and which will 15 when in position hold a skirt or other garment securely and in such a manner as to prevent loss of form from creasing and the like.

One of the advantages resulting from the 20 use of my improved garment-hanger lies in its adaptability to garments of different size, and particularly in its adaptation to skirts having different-sized waistbands, as will readily be observed from an inspection of the 25 drawings, wherein—

Figure 1 is a side view of my improved hanger; and Fig. 2 is a section of the same, showing an end view of one of the hanger arms.

1 is a rod of any suitable material. Attached to this rod is a hook 2, by which the hanger may be suspended. 3 3 are depending oppositely-disposed arms adapted when in normal position to move freely upon and 30 along said rod 1. 4 4 are stops to prevent the arms 3 3 from slipping off the rod. In the preferred form shown each of these arms 3 3 is shaped from wire, the upper portion forming a clamp 31 in the shape of a coil of 35 sufficient length to give a proper clamping surface. The lower portion of this arm, as shown at 32, is shaped according to the article to be suspended, in the case shown a skirt. This clamp 31 is just large enough in 40 diameter to permit of its free movement relatively to the rod when not in use; but when

the lower portion 32 is pressed down and inward, as in the case when a garment is being suspended, the clamp 31 clutches the rod 1, and thereby prevents its movement along 50 the same. The normal position of these arms is indicated in full lines, while their position when in use is shown by dotted lines.

In operation the arms 3 3 are first moved toward the hook 2. Then the garment is 55 placed over the lower portions 32 32, after which the arms are moved outward as far as the garment will permit, the weight of the garment upon the lower portions 32 32 of the arms 3 3 then causing the clamps 31 31 to 60 frictionally clutch the rod with the result heretofore stated.

A modified structure might readily be provided wherein a hollow rod is substituted for the solid one, the rod having a longitudinal 65 slot in its under side, the arms 3 3 moving within the rod instead of outside of the same, as shown above.

Various other modifications of my improved device might be made without departing from the scope of my invention.

What I claim is—

1. A garment-hanger comprising a single rod and two members adjustable thereon and with relation to each other, each member 75 consisting of a single piece of wire having one end formed into a coil slideable on said rod and the other end formed into a broad, yielding, outwardly and downwardly extending loop located beneath said rod. 80

2. A garment-hanger comprising a rod of substantial diameter, projecting knobs carried by the opposite ends thereof and adjustable clamping and supporting members, each of said members consisting of a single piece 85 of wire having one end coiled around said rod and having the other end formed into a supporting member.

CHARLES H. GAGE.
